UNITED STATES PATENT OFFICE.

JENS O. JENSEN, OF BALTIMORE, MARYLAND.

OIL-COKING STILL.

Application filed January 20, 1921. Serial No. 438,607.

The invention relates to the construction of oil stills, the object being to increase the life thereof and improve the operation and the quality of the products.

5 In the accompanying drawings—

Fig. 1 is a side elevation of an oil still embodying my present invention, a portion being broken away to show the interior in longitudinal section. Fig. 2 is an enlarged 10 section on the line 2, 2 of Fig. 1. Fig. 3 is an enlarged section of the left hand end of the still, as shown in Fig. 1, and on the line 3, 3 of Fig. 2, showing in elevation the inserted beams E. Fig. 4 is a horizontal 15 section on the line 4, 4 of Fig. 1.

Similar letters of reference indicate like parts.

A is an elongated cylindrical oil still of known type. On the sides of the still are 20 lugs H which rest upon vertical standards I which are preferably beams of H-shaped cross section, the lower parts of which are imbedded in the end piers B and the intermediate piers C: said piers being of masonry. 25 From said intermediate piers the still is separated by narrow spaces D. When heated and so expanded, the still closes said spaces D and bears upon the intermediate piers C. The oil to be distilled is placed in the still, 30 and deposits its coke residuum upon the bottom of the still, as shown at G. The depth of the deposit will depend upon the grade of oil distilled. Where, for example, the still is, say, forty feet in length and 35 fourteen feet in diameter, with a certain grade of oil the depth of the coke deposit may be, say, twenty-six inches.

In practically using oil stills such, for example, as shown at A, I have found that the 40 bottom sheets of the still are liable to sag between their supports and also to become rapidly deteriorated by the high heat to which they are subjected; and that the heat is not uniformly distributed through the 45 coke deposit but is greatest at the bottom and progressively less to the upper surface of said deposit.

I have eliminated both of these difficulties as follows: Within the still and on the bottom thereof, I rivet a number of parallel longitudinal iron beams E, preferably spaced at equal distances apart and introduced into the still through the man-holes F. The depth of these beams should preferably

be such that their upper surfaces do not 55 come above the upper surface of the coke deposit and lie some inches below said deposit surface. Thus in the preceding example, where the coke deposit is assumed to be twenty-six inches deep, the beams may 60 be about twenty inches deep. Any desired number of these beams may be used. In the drawings I show three, each beam being preferably made in sections placed end to end. The joints between the sections of 65 each beam are preferably staggered with respect to the joints between the sections of an adjacent beam, and it is further preferable that the joints should come directly above the several intermediate supports. 70

These beams hold up the bottom sheets of the still between the supports and effectually prevent their sagging when highly heated. Being securely joined in close metallic contact with the floor of the still they also conduct heat from the bottom to the upper part of the coke deposit and thus deliver said heat to the places in said deposit when normally the heat is lowest, thereby insuring a more uniform heat distribution throughout 80 said deposit. I have found by actual experiment that the presence of the beams shortens the coking time by twenty per cent, and that there is also produced greater economy of fuel and increased life of said 85 bottom sheets because the heat is conducted away therefrom.

I claim:

1. An oil coking still of the type set forth, having its floor portion reinforced by a plurality of longitudinal beam members secured to and in close metallic contact with the interior surface of said floor portion and projecting upwardly therefrom to distribute heat to the still contents. 90

2. An oil coking still of the type described having its floor portion disposed over and adapted to be supported by one or more foundation piers, and a longitudinal interior beam member spanning said piers and secured to and in close metallic contact with the interior of said floor, whereby said floor portion is stiffened and the heat is distributed to the interior of the coke. 100

In testimony whereof I have affixed my 105 signature.

JENS O. JENSEN.
